DESIGN FOR A CRIBBAGE BOARD

Victor J. McGonigle and Wilson I. Thomas,
Richmond, Calif.

Application July 7, 1944, Serial No. 114,336

Term of patent 14 years

(Cl. D34—5)

To all whom it may concern:

Be it known that we, Victor J. McGonigle and Wilson I. Thomas, citizens of the United States of America, residing at Richmond, in the county of Contra Costa, and State of California, have invented a new, original, and ornamental Design for a Cribbage Board, of which the following is a specification, reference being had to the accompanying drawing, forming a part thereof.

The figure is a plan view of a cribbage board showing our new design. The article is of conventional thickness.

We claim:

The ornamental design for a cribbage board, substantially as shown and described.

VICTOR J. McGONIGLE.

WILSON I. THOMAS.
